UNITED STATES PATENT OFFICE.

JAMES O'HARA, OF PITTSBURG, PENNSYLVANIA.

IMPROVEMENT IN RETORTS FOR DISTILLING OILS FROM COAL.

Specification forming part of Letters Patent No. 22,573, dated January 11, 1859.

To all whom it may concern:

Be it known that I, JAMES O'HARA, of Pittsburgh, in the county of Allegheny and State of Pennsylvania, have invented a new and useful Improvement in Retorts for Distilling Coal in the Manufacture of Oils; and I do hereby declare that the following is a full, clear, and exact description of the same, reference being had to the accompanying drawing, forming part of this specification, said drawing representing a central vertical section of a retort with my invention applied.

This invention consists in the employment within an upright retort for distilling coal in the manufacture of coal-oil of an upright screw of a smaller circumference than the interior of such retort, arranged with its axis in or nearly in the center thereof, and having imparted to it a rotary motion in such a direction as to cause the continuous elevation of the central portion of the charge of coal, which elevation is necessarily accompanied by the continuous descent of the exterior portion by gravitation, and consequently a positive continuous and uninterrupted circulation of the coal up the center and down the sides of the retort is produced, so that every particle of coal in turn is caused to pass through the hottest part of the retort, and all the particles subjected to a similar action of the heat, and hence a more perfect distillation is effected.

To enable others skilled in the art to fully understand my invention, I will describe its construction and operation.

A is the retort, of iron, fire-clay, or other substance, having cylindrical sides, and its top and bottom convex, or of other form. This retort is intended to be heated by any of the methods generally employed for heating such retorts, and to be furnished with a door at the top for charging it with coal, and one at the bottom for discharging the coke, and with a pipe at the top for conveying the vapors of distillation to the condenser.

B is the revolving screw for producing the circulation in the retort, having one or more threads, and being made as small as possible at its center, so as to give it the greatest practicable depth of thread in proportion to its external circumference, which should be such as to encircle an area equal to about half the horizontal area of the retort. This screw is

attached to a shaft, C, which passes through the top of the retort, and is fitted to and supported by bearings in a suitable frame-work erected above, and it may or may not have a bearing in the bottom of the retort. The opening in the top of the retort where the said shaft C passes through should be luted. The said shaft may be driven by any convenient means to produce a continuous revolving motion of the screw, the velocity of which should be such as to keep up an active circulation—say thirty (30) revolutions per minute; but such velocity may be varied very materially.

In the particular example of my invention represented the screw has a right-handed thread, and consequently rotates in the direction of the arrow shown on the shaft to produce the elevation of the coal, which occupies the central portion of the retort between its threads. It is obvious that the continuous elevation of the central portion of the charge of coal would leave an empty space at the center of the bottom of the retort, but that the coal occupying the portion of the retort outside of the screw descends continually by gravitation to fill said space. The coal, as it is caused by the action of the screw to arrive at the surface, falls toward the sides of the retort to fill the space left by the descending portion; and hence it will be readily seen that a continuous circulation of a positive character is kept up, and every part of coal must in its turn be brought to the hottest part of the retort, which, when the usual methods of heating are employed, is generally at or near the bottom.

The screw may be surrounded by a stationary cylinder, which fits it closely, but which extends neither to the top nor bottom of the retort, but permits the passage of the coal under and over it. The cylinder will cause a more perfect and positive upward and downward circulation; but it is liable to objection on account of the friction produced between it and the screw.

I do not claim, generally, the use of a stirring apparatus within a retort, as I am aware that such apparatus has been used in retorts for some distilling processes; but

What I claim as my invention, and desire to secure by Letters Patent, is—

The employment, in an upright retort for

distilling coal, of a revolving screw of a circumference smaller than the interior of the retort, so applied that while by its revolution it produces a continuous elevation of the central portion of the charge it permits and causes a continuous descent of the surrounding portion by gravitation, and thus produces

a positive continuous and uninterrupted upward and downward circulation, substantially as and for the purpose herein set forth.

JAS. O'HARA.
